UNITED STATES PATENT OFFICE.

WALTER D'A. RYAN, OF LYNN, MASSACHUSETTS, AND LONGLEY L. SAGENDORPH, OF PHILADELPHIA, PENNSYLVANIA, ASSIGNORS OF ONE-THIRD TO HARLAN P. LLOYD, OF CINCINNATI, OHIO.

CEILING CONSTRUCTION.

SPECIFICATION forming part of Letters Patent No. 741,593, dated October 13, 1903.

Application filed January 19, 1903. Serial No. 139,644. (No model.)

To all whom it may concern:

Be it known that we, WALTER D'A. RYAN, a subject of the King of Great Britain and Ireland, and a resident of Lynn, Massachusetts, and LONGLEY L. SAGENDORPH, a citizen of the United States, and a resident of Philadelphia, Pennsylvania, have invented 5 certain Improvements in Ceiling Construction, of which the following is a specification.

Our invention consists in certain improvements in the detail construction of metallic ceilings, having for its object the provision 10 of means whereby the curved metallic plates comprising the reflecting-surface for a lamp 15 may be made to join rectangular ceiling-plates of any of the standard constructions at present known to the art, a further object being to provide a construction such that the fitting of standard ceiling-plates to such curved 20 pieces may be quickly and easily accomplished and that without the necessity for or use of unsightly joints. These objects we attain as hereinafter set forth, reference being had to the accompanying drawings, in 25 which—

Figure 1 is an inverted plan view illustrating a section of a metallic ceiling and showing our improved construction by which standard ceiling-plates of varying sizes may 30 be fitted to a circular metallic reflecting-section. Fig. 2 represents an inverted plan view of a special form of section, showing the applicability of our improved construction thereto; and Fig. 3 is an enlarged sectional 35 elevation taken on the line 3 3, Fig. 1, illustrating the detail construction of a ceiling-section made according to our invention.

In the above drawings, A represents a reflecting ceiling-section, which in the case 40 illustrated is made in two parts, of which one, a, consists of a substantially conical surface provided with a number of annular projections or corrugations of increasing amplitude from the apex of said surface to its base, 45 while the second part, a', of said surface is concave in form and extends downwardly and outwardly from the base of said conical surface. Any desired source of light is placed in the line of the vertical axis of the surface

a and adjacent to its apex, this source being 50 in the device illustrated an electric-arc lamp of the inclosed-arc type.

In order that the above device may have a slightly appearance and may at the same time be conveniently united to standard rectangular metallic ceiling-plates, we unite to the 55 lower edge of the surface a' an upwardly-extending annular portion a², which as it approaches the level of the ceiling is provided with one or more annular flanges a³, having 60 grooves a⁴.

The ceiling represented at B has in the case illustrated a series of furring-strips, of which one is shown at b', and to these the reflecting 65 structure as well as the metallic ceiling-plates 70 are fastened in any desired manner, being thereby retained in position.

By reference to Fig. 1 it will be seen that we provide four sections or pieces C, designed to surround the reflecting-section A, forming 75 together a figure whose external configuration is angular and which has a cut-away portion wholly within the area inclosed by its periphery conforming to the shape and for the accommodation of the said reflecting-section. Both of the outer and inner edges of these junction-sections C are flanged and either recessed or grooved, as indicated at c, there being also, as above noted, corresponding recesses or grooves a⁴ in one of the flanges 80 projecting from the annular portion a² of the reflecting-surface. It will be seen, therefore, that by the use of the sections C the curved section A, which may be made, as shown in Figs. 1 and 2, either circular or elliptical in 85 outline, is extended so that angular ceiling-plates D, which in the case illustrated are four-sided and of various sizes, may be united therewith to form a regular and slightly construction of ceiling, the grooved or recessed 90 portions d of said ceiling-plates fitting into the correspondingly-formed recessed portions c of the junction-pieces C and these in turn uniting with the grooved flanges of the curved reflecting-section. 95

We claim as our invention—

1. The combination of a series of ceiling-plates, with a light-reflecting section, said

section forming a portion of the ceiling and being joined to said plates, substantially as described.

2. The combination of a series of ceiling-
5 plates, with a section placed to be substan-
tially continuous therewith, said section hav-
ing a light-reflecting portion, substantially as
described.

3. The combination of a series of ceiling-
10 plates, a curved reflecting ceiling-section and
junction-plates uniting the ceiling-plates with
said reflecting section, substantially as de-
scribed.

4. The combination of a reflecting ceiling-
15 section having a curved outline, and a series
of junction-sections of a construction to fit
the ceiling-section, said junction-sections be-
ing of an angular exterior configuration, with
20 a series of ceiling-plates constructed to unite
with said junction-sections, substantially as
described.

5. The combination of a ceiling-section
having a curved outline, said section having
a grooved flange surrounding the same, a se-
25 ries of junction-sections having portions de-
signed to fit said grooves of the curved sec-

tion and to form together a figure of angular
outline, and ceiling-plates also having grooved
portions and designed to unite with said junc-
tion-sections to form a complete ceiling, sub- 30
stantially as described.

6. The combination of a light-reflecting
ceiling-section of curved outline, an annular
flanged portion surrounding the same, said
flanged portion being grooved, a series of 35
junction-sections having grooved portions
designed to fit the grooved portion of the
curved section, said junction-sections com-
pletely surrounding the curved section and
being rectangular in outline, with a series of 40
ceiling-plates grooved along their edges and
designed to be united to the correspondingly-
grooved portions of said junction-sections,
substantially as described.

In testimony whereof we have signed our 45
names to this specification in the presence of
two subscribing witnesses.

WALTER D'A. RYAN.
LONGLEY L. SAGENDORPH.
